VARIABLE RESISTOR

Henry H. Cary, Alhambra, and Douglas George Marlow, Altadena, Calif., assignors to National Technical Laboratories, South Pasadena, Calif., a corporation of California

Application June 23, 1941, Serial No. 399,300

20 Claims. (Cl. 201—56)

Our invention relates to resistances for electric circuits, with special reference to variable resistors for service as rheostats, potentiometers, voltage dividers, and the like.

The general object of our invention is to provide an exceptionally compact variable resistor offering finely graduated control over a relatively extensive range of resistance values. A further general object is to provide such a variable resistor that is structurally efficient, dependable in service, and relatively inexpensive to manufacture.

The invention includes a resistive conductor wound into a spiral, and in the preferred form of the invention the resistive conductor is wound into a double spiral comprising a minor spiral of relatively numerous small-diameter turns and a major spiral of relatively few large-diameter turns formed by the minor spiral. In some practices of our invention the major spiral may have the configuration of a plane curve formed by a point that moves around a fixed center and continually increases its distance from the center; in other practices of our invention the spiral may define a cylindrical configuration like a screw-thread. Various objects of our invention relate to the manner of arranging a movable contact for cooperation with a spiral resistance. Among these objects are: to employ the spiral conductor as a mechanical guide for the contact; to limit the area of electrical contact with the spiral by providing a separate non-conductive guide element for mechanical engagement with the spiral; to reduce friction and wear by providing for rolling engagement of the non-conductive guide element with the spiral; and to provide a separate guide element without limiting the range of spiral movement of the contact along the spiral.

A further object in mind is to provide for substantially constant mechanical pressure against the spiral resistance over the entire range of contact movement. In this regard our invention is characterized by the concept of movably mounting the contact on a support that, in effect, floats in a position transversely of and equidistant from the turns of the spiral resistance. More specific objects, to appear later relate to the manner of yieldingly mounting such a contact-support to provide the desired constancy of pressure on the part of the movable contact.

Further objects and advantages of our invention will be apparent from the detailed descrip-

tion to follow taken with the accompanying drawings.

In the drawings which are to be considered as illustrative only:

5 Fig. 1 is a longitudinal section through a preferred embodiment of our invention;

Fig. 2 is an end view of the device taken as indicated by the arrow 2 in Fig. 1, a casing cover being removed to reveal the interior of the de-

vice;

Fig. 3 is a transverse section taken as indicated by the line 3—3 of Fig. 1;

Fig. 4 is a transverse section taken on the broken line 4—4 of Fig. 1;

15 Fig. 5 is a longitudinal section taken as indicated by the line 5—5 of Fig. 1;

Fig. 6 is a phantom view showing selected internal elements in perspective;

Fig. 7 is a sectional view of a second form of 20 our invention;

Fig. 8 is a section taken as indicated by the broken line 8—8 of Fig. 7;

Fig. 9 is a sectional view of a third form of our invention; and

25 Fig. 10 is a section taken as indicated by the line 10—10 of Fig. 9.

The principal parts of the preferred form of our invention shown in Figs. 1 to 6 include a spiral resistance generally designated 20 in a 30 cylindrical casing 21, the two comprising a resistance assembly, a rotary control means generally designated 22 including an operating knob 23 and an operating shaft 24, a contact-support generally designated 25 carried by the rotary control means, and a contact assembly generally designated 27.

The cylindrical casing 21 is closed at one end by a cover 28 which is normally retained in a releasable manner by a resilient split ring 30, the 40 cover and the cylindrical casing being provided with complementary grooves 31 and 32 respectively to seat the ring. The cylindrical casing 21 is also provided with a tubular member 33 that serves as a bearing for the operating shaft

45 24 and is externally threaded to receive a nut 35. Such a construction permits the device to be mounted on a panel 36 in the manner indicated in Figs. 1 and 5, the tubular member 33 extending through a panel aperture 37 and the 50 panel being gripped between the nut 35 and an annular shoulder 38 of the tubular member. The operating knob 23 is secured on the operating shaft 24 by a suitable setscrew 40 after the cylindrical casing 21 is mounted on the panel.

55 The spiral resistance 20 preferably is a rela-

tively fine wire closely wound in numerous turns 42 on a core 43, which core in turn is wound in turns 45 to form a second spiral. The resistive wire may be said to have the form of a double spiral in which the turns 42 of relatively small diameter on the core form a minor spiral and the turns 45 of the core of larger diameter form a major spiral. The core 43 may be fabricated from any suitable material, but in the construction shown comprises a relatively heavy copper wire with an adequate coating of insulating material. The relatively fine wire forming the small-diameter turns 45 on the core 43 is a resistive conductor with an insulating coat that is partially removed after the winding operation to expose the wire for cooperation with the contact assembly 27. It will be noted that both the minor spiral and the major spiral are closely wound to make an exceptionally compact device and that an exceedingly large number of the small turns 42 provide exceptionally close control over an exceptionally extensive range of resistance values.

One or both ends of the resistance may be connected to external terminals on the cylindrical casing 21. In the present construction two such terminals 46 are provided, the terminals being in the form of metal clips extending through the wall of the cylindrical casing. While the spiral resistance 20 may be mounted in the cylindrical casing 21 in any suitable manner in the various practices of our invention, one feature of our preferred practice is the conception of securing the spiral resistance in the casing by expanding the spiral into engagement with the casing. In the illustrative construction, one end of the core 43 rests against a stop shoulder 47 formed in the cylindrical casing 21 and the other end of the spirally wound core abuts a second stop shoulder 48 provided by a retaining ring or sleeve 50 that is telescoped into the cylindrical casing. In the assembly procedure, the spiral resistor is placed loosely in the cylindrical casing 21 with the two terminals 46 extending through suitable slots 51 in the casing wall and then the retaining sleeve 50 is inserted and rotated against the outer end of the spiral core 43 to expand the spiral. The slots 51 are cut to permit some latitude in the location of the two terminals 46 and to avoid interfering with the transmission of pressure through the spiral resistance in this assembly procedure. After the retaining sleeve 50 is rotated against the end of the resistor to create the desired expanding pressure, the retaining sleeve is anchored in place by suitable means such as one or more pins 52 penetrating the cylindrical casing 21.

In the present form of our invention the contact-support 25 includes a polished rod 53 on which the contact assembly 27 is slidably mounted. It is contemplated that the polished rod 53 will be mounted on the rotary control means 22 in a yielding or floating manner, but will always be maintained substantially parallel to the axis of the major spiral, i. e., the axis of the spiral formed by the core 43. The purpose of yieldingly mounting the polished rod 53 and at the same time holding the rod in the parallel relationship is to provide for uniform pressure of the contact assembly against the spiral resistance throughout the entire range of adjustment. While various mechanical arrangements may be employed for mounting the polished rod 53 on the rotary control means 22 in the required manner we prefer to employ a pair of resiliently biased

parallel arms 55, and while the two arms may be biased by resorting to various expedients we prefer to make the two arms of resilient material and thereby avoid the necessity of providing separate resilient means.

In the construction shown, the inner end of the operating shaft 24 carries what may be termed a rotary base member 56 of non-conductive material on which the two arms 55 are mounted by a suitable screw 57 and small plate 58, the arms comprising flexible metal strips with bent ends 60 overlapping between the base member and the small plate. The outer ends of the flexible arms 55 carry a head member 61 which in turn carries the previously mentioned polished rod 53 by one end. The head member 61 comprises a metal bar and is attached to the two arms 55 by a rivet 62, the rivet penetrating bent ends 63 of the two arms and a small retaining plate 65. Since the two arms 55 are resilient, they permit the polished rod 53 to move relative to the surrounding spiral resistance 20 and the fact that the two arms are parallel and also of equal length causes the polished rod to be maintained substantially equidistant from all of the large-diameter turns 45 of the spiral resistance. Preferably the rotary base member 56 provides a slot 66 into which the free end of the polished rod 53 extends, the slot permitting the end of the polished rod to move freely toward and away from the spiral resistance 20 but preventing any substantial lateral movement with respect to the rotary control.

In designing the contact assembly 27, we contemplate arranging an electrical contact to move freely along the length of the polished rod 53 and to be guided in such movement by mechanical engagement with the large-diameter turns 45 of the spiral resistance. The electrical contact and the means for guiding the electrical contact by mechanical engagement with the spiral resistance may be the same member, i. e., an electrical contact may be designed for guiding engagement with the spiral resistance; it is desirable, however, to provide a separate guide member of non-conductive material operatively connected with the electrical contact. It may be noted that the spiral resistance 20 is closely wound both with respect to the small-diameter turns 42 and the large-diameter turns 45 for the sake of compactness. It is difficult to combine in one member the function of contact and contact guide means for cooperation with such a closely wound spiral resistance without causing electrical contact to be made simultaneously with several of the small-diameter turns 42 in two or more of the large-diameter turns 45, a condition that is undesirable in some electrical installations. We prefer, then, to employ a separate non-conductive guide means and further prefer to design such guide means for rolling contact with the spiral resistance 20.

In the particular construction shown by way of example in Figs. 1 to 6, a contact-carrier 70 has two spaced legs 71 with an interconnecting sleeve 72 for sliding engagement with the polished rod 53 and has an arm 73 slidably extending into a slot 74 in one of the parallel arms 55 (Figs. 3 and 6) to prevent rotation of the contact-carrier about the axis of the polished rod. Rotatably and slidably mounted on the polished rod 53 between the two legs 71 of the carrier is a guide member in the form of a wheel 75 of non-conductive material, which wheel is preferably tapered at its periphery to a thin edge to seat into the spiral groove that is formed by the

large-diameter turns 45 of the spiral resistance 20. The spiral resistance serves as a track for the wheel. A contact in the form of a resilient metal arm 76 with an end curved as shown is mounted across the ends of the two carrier legs 71 to follow the spiral path defined by the large-diameter turns 45 and thereby shift from one of the small-diameter turns 42 to another over the length of the resistance 20. Current may be taken from the contact 76 by any suitable means, not shown in detail, electrically connected to any metallic portion of the rotating structure, such means being well known in the art. For example, a brush contact may engage the head member 61 in this connection.

Preferrably the retaining sleeve 50 is formed with an inner spiral groove 78 in continuation of the spiral groove formed by the spiral resistance 20, so that the guide wheel 75 may overrun the end of the spiral resistance and thereby permit the contact 76 to reach the extreme end of the spiral resistance. We further prefer to provide suitable stop means for abutment by the contact-carrier 70 when the contact 76 reaches either end of the spiral resistance. Thus, we show in the drawings a stop shoulder 80 formed in the cylindrical casing 21 and a second stop shoulder 81 provided by the retaining sleeve 50.

The operation of this first form of our invention may be readily understood from the foregoing detailed description. It is apparent that rotation of the knob 23 causes the contact 76 to move along a spiral path conforming to the spiral configuration of the resistance and that relatively close adjustment of resistance values may be had over a relatively extensive range of values. Since the pressure of the contact assembly toward the surrounding spiral resistance is provided by the resilient parallel arms 55 and since the polished rod 53 is substantially equidistant from the several large-diameter turns 45 of the resistance, the pressure exerted through the contact carrier 70 is substantially uniform throughout the whole range of adjustment.

In the second embodiment of our invention depicted in Figs. 7 and 8, we apply the same principles to an arrangement in which a contact moves around the exterior of a spiral resistance. Fig. 7 shows a cylindrical casing 85 mounted on a panel 86 in the previously described manner, an operating shaft 87 extending through the panel and carrying the usual operating knob 88. The cylindrical casing 85, which is provided with a removable cup-shaped cover 93, has an interior cylindrical wall 91 that is embraced by a spiral resistance 92 and by a sleeve 93. The resistance 92 which is connected to suitable external terminals (not shown) is secured on the cylindrical wall 91 in any suitable manner and is similar in construction and arrangement to the previously described spiral resistance 20, the configuration including a similar minor spiral of small-diameter turns and a major spiral of large-diameter turns.

The means for supporting a movable contact in the arrangement shown in Figs. 7 and 8 includes a base member 95 fixedly embracing the operating shaft 87, a pair of flexible arms 96 mounted in parallel relation on the base member, and a head member 97 mounted on the ends of the flexible arms 96. The head member 97 has a relatively large aperture 98 surrounding the operating shaft 87 to permit movement relative to the operating shaft and carries at its outer end a polished rod 100 that is positioned outside

the spiral resistance 92 and disposed parallel to the operating shaft 87. A contact-carrier 101 that is slidably mounted on the polished rod 100 carries both the usual contact 102 and guide wheel 102 and is provided with a short arm 105 to prevent rotation about the axis of the polished rod. In this construction the short arm 105 extends into a guide slot 106 in a special guide bar 107 that is non-rotatively retained on the end of the operating shaft 87 by a suitable nut 108. Preferably the guide bar 107 is provided with an inwardly bent end 110 that has a guide slot 111 for the free end of the polished rod 100. The two flexible arms 96 are biased to urge the polished rod 100 toward the cylindrical wall 91 for the purpose of maintaining the guide wheel 103 in the groove formed by the spiral resistance and for the further purpose of holding the contact 102 against the spiral resistance.

20 The third form of our invention shown in Figs. 9 and 10 is based on the novel concept of arranging a double-spiral resistance in substantially one plane for installations where available space for the variable resistor is limited in one dimension. 25 A casing 112 including a removable cup-shaped cover 113 is shown mounted in the previously described manner on a panel 115. A spiral resistance 116 comprises a coated wire wound on a core 117 that has the configuration of a flat 30 spiral rather than a cylindrical spiral. As best shown in Fig. 10 this arrangement provides numerous small-diameter turns 118 of a minor spiral and larger turns 120 of a major spiral. The spiral resistance 116 may be secured in place 35 in any suitable manner and attached to suitable external terminals (not shown). In the particular arrangement shown, the spiral resistance 116 is surrounded by a ring 121 of non-conducting material having a spiral groove 122 in continuation of the spiral groove formed by the resistance.

An operating shaft 123 carrying the usual operating knob 125 is journaled in one bearing provided by a tubular member 126 and in a second bearing 127 in the casing cover 113. Suitably mounted on the operating shaft 123 in a manner permitting movement toward and away from the spiral resistance 116 is a contact-support arm 130. As shown in Fig. 9 the arm 130 may be carried by a ring 131 that is slidably keyed to the operating shaft 123 and is integral with an over-sized cylinder 132 surrounding the shaft. One bearing point for supporting the arm 130 is provided by the ring 131, and a second bearing point is provided by a collar 133 that is threaded onto the operating shaft 123 inside the cylinder 132. A suitable spring 135 embracing the operating shaft 123 between the ring 131 and the collar 133 serves as the required means for urging the contact-support arm 130 toward the plane of the spiral resistance 116.

65 The contact-support arm 130 engages both ends of a polished rod 136 and is formed with a portion 137 parallel with the polished rod. The usual contact-carrier 140 is slidably mounted on the polished rod 136 and prevented from rotation by an arm 141 that extends into a guide slot 142 in the portion 137 of the support arm. The contact-carrier 140 has the usual contact 70 143 pressing against the spiral resistance 116 and has the usual guide wheel 145 in mechanical engagement with the spiral resistance. Rotation of the operating shaft 123 by manipulation of the operating knob causes the contact 143 to sweep in a flat spiral path conforming to the configu-

ration of the flat spiral resistance, and uniform pressure against the spiral resistance throughout the range of adjustment is maintained by the concealed spring 135.

The three selected embodiments of our invention described in detail herein for the purpose of disclosure will suggest to those skilled in the art various changes and substitutions under our inventive concept; we reserve the right to all such departures from our described arrangements that come within the scope of our appended claims.

We claim as our invention:

1. A variable resistor having: a spiral resistive conductor, adjacent turns of the spiral forming a spiral groove; a contact movably touching a turn of said spiral conductor; a guide member of non-conductive material movably extending into said spiral groove, said guide member being connected with said contact to confine the contact to move in a spiral path conforming to the spiral turns of the conductor and in such manner that said contact engages one turn of said spiral conductor at a time while advancing along said spiral path guided by said guide member; and means for advancing said guide member progressively along said spiral groove.

2. A variable resistor having: a resistive conductor wound to form a spiral; control means rotatable about the axis of said spiral; a contact-support extending across the turns of said spiral in substantially equidistant spacing from the individual turns; means including a parallel linkage mounting said contact-support on said control means to control the movement of the contact-support relative to said spiral while maintaining said equidistant spacing from the turns of the spiral, said means including means yieldingly urging said contact-support toward said spiral; and a contact movably mounted on said contact-support and mechanically guided by the turns of said spiral to move along and in engagement with said spirally-wound conductor.

3. A variable resistor having: a stationary resistive conductor wound to form a spiral; control means rotatable about the axis of said spiral; a contact-support traversing the turns of said spiral in spaced relationship therewith and rotatable with said control means; means for mounting said contact-support to move in a direction toward and away from said spiral; yielding means for urging said contact-support toward said spiral; a contact movably mounted on said contact-support and engaging a turn of the spirally-wound conductor; a guide member movable along and in contact with the turns of said spiral; and means for operatively connecting said guide member and said contact to move said contact along said spirally-wound conductor as said guide member advances along the turns of said spiral.

4. A variable resistor having: a resistive conductor wound to form a spiral having an end; a contact movably touching one turn of said spiral conductor; a guide member of non-conductive material spaced from and connected with said contact to guide the contact, said guide member movably engaging said spiral at a position spaced from, and closer to said end than, the point of engagement of said contact with said turn whereby the guide means will approach said end of the spirally-wound conductor in advance of the contact; means to rotate said contact and guide member together about the axis of said spiral; and means at said end of said spiral continuing the configuration of the spiral to guide said guide

member beyond the end of the spiral to permit said contact to reach the end of the spiral.

5. A variable resistor having: a resistive conductor wound to a spiral forming a spiral groove; a contact movably touching a turn of said spiral; a wheel riding in said groove, said wheel being connected with said contact to guide the contact; and control means to cause relative rotation of said contact and wheel with respect to said spiral about the axis of said spiral.

6. A variable resistor having: a resistive conductor wound to a spiral of closely adjacent turns forming a narrow spiral groove; a contact movably touching a turn of said spiral; a wheel of non-conductive material riding in said groove for guidance by two adjacent turns of the spiral, said wheel being connected with said contact to guide the contact; and control means to move said contact and wheel together about the axis of said spiral.

7. A variable resistor having: a conductor wound substantially equidistant to an axis to form a spiral about said axis; rotary control means coaxial with said spiral; a pair of parallel arms on said control means; a contact-support supported by said arms in parallel relation with the axis of the spiral; and a contact assembly slidably mounted on said contact-support including means engaging the turns of said spiral to advance said contact assembly along said contact-support, said contact assembly including a contact engaging a turn of the spirally-wound conductor; and means for resiliently biasing said contact-support toward the spiral.

8. A variable resistor having: a conductor wound substantially equidistant to an axis to form a spiral about said axis; rotary control means coaxial with said spiral; a pair of parallel arms on said control means; a contact-support

supported by said arms in parallel relation with the axis of the spiral, said parallel arms being resiliently biased to urge said contact-support toward the spiral; a contact slidably mounted on said contact-support for electrical engagement with a turn of the spirally-wound conductor; and a guide member formed of non-conducting material engaging said spiral to be mechanically guided by the turns of said spiral, said guide member being operatively connected to said contact to guide same along said spirally-wound conductor.

9. A variable resistor having: a resistance assembly including a conductor forming a spiral; control means rotatable about the axis of said spiral; a contact-support extending across the turns of said spiral in substantially equidistant spacing from the individual turns of the spiral, said contact-support being carried by said control means for rotation about the axis of the spiral; contact means mounted on said contact-support for movement longitudinally thereof, said contact means being in contact with said conductor; and guide means spaced a substantially constant distance from said contact means, said guide means being connected with said contact means and engaging a track provided by the spiral configuration of said conductor, there being insulating material to prevent flow of current from the conductor through said guide means

70 to said contact means.

10. A variable resistor having: a resistance assembly including a conductor forming a spiral; control means rotatable about the axis of said spiral; a contact-support extending across the turns of said spiral in substantially equidistant

spacing from the individual turns, said support being carried by said control means for rotation about the axis of the spiral; means yieldingly urging said contact-support toward said conductor; contact means carried by said contact-support and extending into contact with said spiral conductor of said resistance assembly; and contact-advancing means carried by said contact-support to receive force exerted by said yielding means and limit the movement of the contact-support toward said resistance assembly, said contact-advancing means being movable along said contact-support and being operatively connected with said contact means and in guiding engagement with said resistance assembly to control the movements of said contact means in response to rotation of said control means.

11. A variable resistor as set forth in claim 10 in which said contact-advancing means is a wheel engaging said spiral conductor, there being insulating material to prevent flow of current from said conductor through said wheel to said contact means.

12. A variable resistor having: a cylinder providing an inner surface; a resistive conductor wound into a spiral lying against the inner surface of said cylinder; stop means fixed relative to said cylinder in abutment with one end of said spiral; a sleeve telescoped in said cylinder and rotatable therein during assembly of the cylinder and spiral, said sleeve providing a stop surface acting against the other end of said spiral in such manner that rotation of said sleeve relative to the cylinder will tend to unwind the spiral to expand against the inner surface of said cylinder, thereby to immobilize the spiral at substantially uniform diameter; means for locking said sleeve against rotation within said cylinder when said spiral has been expanded; a contact within said spiral electrically cooperating with said conductor; and means to move said contact adjustably along a spiral path conforming to said spiral.

13. In a variable resistor, the combination of: a resistive conductor wound as a spiral providing a plurality of turns; control means rotatable about the axis of said spiral; a rod extending across the turns of said spiral in substantially equidistant spacing from the individual turns; arm means operatively connecting said rod to said control means to rotate therewith, said arm means providing a portion extending transversely across said turns but spaced therfrom, said portion providing a slot; a contact carrier slidable along said rod and providing an arm extending into said slot to prevent rotation of said contact carrier on said rod, said contact carrier including a contact engaging a turn of said spiral; and guide means carried by said contact carrier and engaging said spiral to advance said contact carrier along said rod to move said contact progressively along said spiral.

14. In a variable resistor, the combination of: a resistive conductor wound as a spiral providing a plurality of aligned turns; control means rotatable about the axis of said spiral; a head member; a rod attached to said head member and disposed in a position spaced from and traversing said aligned turns of said spiral; means operatively connecting said head member and its attached rod to said control means to cause said head member and its rod to rotate about the axis of said spiral with said control means, said means including parallel-motion means for resiliently moving said rod toward said aligned turns of said spiral and for maintaining the axis

of said rod substantially parallel to the aligned turns during movement of said rod toward and away from said turns; carrier means slidable along said rod and providing engagement means extending therefrom into engagement with said spirally-wound conductor to advance said carrier means along said rod as said control means is rotated about said axis; and means for preventing rotation of said carrier means relative to said rod during advancement of said carrier means therealong.

15. In a variable resistor, the combination of: a resistive conductor wound as a spiral providing a plurality of turns; control means rotatable about the axis of said spiral and providing a base member adjacent one end of said spiral; a head member adjacent the other end of said spiral; arm means extending between and operatively connecting said head member and said base member; a rod carried by said head member in a position spaced from and traversing said turns of said spiral; carrier means slidable along said rod and providing a contact mounted on said carrier means and engaging a turn of said spiral, said carrier means including also an engagement means extending into engagement with said spiral to advance said carrier means along said rod, said engagement means comprising a guide roller formed of electrical insulating material rotatable on said rod and engaging said spiral at a position spaced from the point of engagement of said contact with said turn, said guide roller being slidable along said rod, and said carrier means including means operatively connected to said guide roller to advance said carrier means and said contact in a spiral path conforming to the turns of said spiral and while said contact and said guide roller are spaced a substantially constant distance from each other; and means for preventing rotation of said carrier means relative to said rod during advancement of said carrier means therealong.

16. In a variable resistor, the combination of: a resistive conductor wound as a spiral providing a plurality of turns; control means rotatable about the axis of said spiral and providing a base member adjacent one end of said spiral; a head member adjacent the other end of said spiral; arm means extending between and operatively connecting said head member and said base member, said arm means being flexible to permit movement of said head member relative to said base member; a rod carried by said head member in a position spaced from and traversing said turns of said spiral, said base member providing a slot into which said rod extends, said slot providing wall means guiding the movement of said rod with respect to said base member; carrier means slidable along said rod and providing engagement means extending into engagement with said spiral to advance said carrier means along said rod; and means for preventing rotation of said carrier means relative to said rod during advancement of said carrier means therealong.

17. In a variable resistor, the combination of: a resistive conductor wound as a spiral providing a plurality of turns including two end turns terminating respectively in ends; a casing providing a surface to contact said turns and a projection extending from said surface to be contacted by one of said end turns, said projection providing a stop shoulder engaging the end of said one end turn of said spiral; a ring rotatable relative to said casing and providing a surface providing a stop shoulder engaging the end of the other

end turn of said spiral whereby turning said ring in said casing will move the turns of said spiral into pressural contact with said surface of said casing in the zone between said projection and said ring; a contact engaging a turn of said spiral; and means for advancing said contact along said spiral.

18. A combination as defined in claim 17, in which said means for advancing said contact along said spiral comprises a guide means engaging said spiral at a position spaced from the point of engagement of said contact with said spiral, and in which said ring provides a spiral groove continuing the configuration of said spiral beyond said stop shoulder of said ring to guide said guide means beyond the adjacent end of said spiral to permit said contact to reach the extreme end of the spiral.

19. A combination as defined in claim 17, in which said surface of said projection of said casing is of spiral configuration to conform in shape to said one of said end turns, and in which said surface of said ring is of spiral configuration to conform in shape to the other of said end turns, and including means for anchoring said ring with respect to said casing when said ring has been turned to move the turns of the spiral into pressural contact with said surface of said casing.

20. A variable resistor having: a resistance

assembly including a conductor forming a spiral; control means rotatable about the axis of said spiral; a contact-support extending across the turns of said spiral in substantially equidistant spacing from the individual turns, said contact-support being carried by said control means for rotation about the axis of said spiral; means for mounting said contact-support to move toward said turns of said spiral while maintaining the substantially equidistant spacing of said contact-support from said individual turns of said spiral, said mounting means including yielding means urging said contact-support toward said conductor; contact means carried by said contact-support and extending into contact with said spiral conductor of said resistance assembly; and contact-advancing means carried by said contact-support to receive force exerted by said yielding means and limit the movement of the contact-support toward said resistance assembly, said contact-advancing means being movable along said contact-support and being operatively connected with said contact means and in guiding engagement with said resistance assembly to control the movements of said contact means in response to rotation of said control means.

HENRY H. CARY.
